(57) **CLAIM**

We claim the ornamental design for a connector position assurance device, as shown and described.

DESCRIPTION

FIG. 1 is a perspective view of a left side of an connector position assurance device showing our new design in an intended environment;

FIG. 2 is a perspective left front side view of the connector position assurance device;

FIG. 3 is a perspective view of a left rear side thereof;

FIG. 4 is a top plan view thereof;

FIG. 5 is a left elevation view thereof; the right elevation view being a mirror image;

FIG. 6 is a rear elevation view thereof; and,

FIG. 7 is a front elevation view thereof.

The bottom of the connector position assurance device is unornamented.

The broken lines are for the purpose of illustrating the environment of the article only and form no part of the claimed design.
